(57) **CLAIM**

The ornamental design for a set of earphones with case, as shown and described.

DESCRIPTION

FIG. 1 is a perspective view of one earphone of the set of earphones with case, shown in isolation, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of the case of the set of earphones with case, shown in isolation, showing my new design;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view of the set of earphones with case, showing my new design; and,

FIG. 16 is another perspective view thereof.

The broken line showing of the case is included for the purpose of illustrating portions of the article and forms no part of the claimed design.

1 Claim, 16 Drawing Sheets
